UNITED STATES PATENT OFFICE.

WILLIAM DAVIS, OF SAN FRANCISCO, CALIFORNIA.

DESIGN FOR A BRIDLE-BIT.

SPECIFICATION forming part of Design No. 16,758, dated June 29, 1886.

Application filed April 26, 1886. Serial No. 200,223. Term of patent 7 years.

To all whom it may concern:

Be it known that I, WILLIAM DAVIS, a citizen of the United States, residing at the city and county of San Francisco, State of California, have invented and produced a new and original Design for Bridle-Bits, of which the following is a specification, reference being had to the accompanying drawing, forming part thereof.

10 The figure is a perspective view of my bridle-bit.

My invention relates to a new design for bridle-bits; and it consists, essentially, in a cheek-piece with ornamental "conchas," and 15 the bar of the mouth-piece located above the conchas.

In the drawing, A is a bridle-bit. B are the cheek-pieces. C is the mouth-piece, here shown as a spade. D is the bar of the mouth-piece, 20 and E are the cross-chains. It will be observed that the cheek-pieces have the couchas b, below which is a light curved shape, b', which terminates at a point at which the cross-chains E enter. The concha, it may be ex-

plained, is exterior of the cheek-pieces, and 25 consists of a round bulging piece suitably ornamented. The bar D of the mouth-piece of my bit is above the conchas, and may be provided with exterior heads, d, of an ornamental nature.

Having thus described my invention, what I 30 claim as new, and desire to secure by Letters Patent, is—

1. In a bridle-bit, the design herein shown and described, the same consisting of the cheek-piece B, having the concha b, and the bar D of the mouth-piece above the concha.

2. In a bridle-bit, the design herein shown and described, the same consisting of the cheek-piece B, having the concha b and the light 40 curved shape b' below, and the bar D of the mouth-piece above the concha.

In witness whereof I have hereunto set my hand.

WILLIAM DAVIS.
